UPHOLSTERY FABRIC

Hugh C. Dugan, Nutley, N.J., assignor to Carlee Corporation, Northvale, N.J.

Filed Apr. 14, 1972, Ser. No. 244,349

Term of patent 14 years

Int. Cl. D5—06

U.S. Cl. D87—3 G

FIG. 2

FIG. 1 is a top plan view of an upholstery fabric showing my new design, a design unit being marked off with dash lines the unit repeating to the left and to the right in regular succession; and

FIG. 2 is a cross sectional view thereof.

I claim:

The ornamental design for an upholstery fabric, as shown and described.
